DESIGN FOR A HANDBAG

Florence N. Lewis, New York, N. Y.

Application August 4, 1936, Serial No. 64,231

Term of patent 7 years

To whom it may concern:

Be it known that I, Florence N. Lewis, a citizen of the United States, residing in New York, county and State of New York, have invented a new, original, and ornamental Design for a Handbag, of which the following is a specification, reference being had to the accompanying drawing, forming a part thereof.

In the drawing:—

Fig. 1 is a perspective view of a handbag embodying my new design in closed position.

Fig. 2 is a perspective view of the bag in open position.

I claim:—

The ornamental design for a handbag, as shown.

FLORENCE N. LEWIS.
